UNITED STATES PATENT OFFICE.

JOHN H. A. BOUSFIELD, OF ST. JOHNSBURY, VERMONT, ASSIGNOR TO E. AND T. FAIRBANKS AND COMPANY, OF ST. JOHNSBURY, VERMONT, A CORPORATION OF VERMONT.

TRACK-SCALE.

1,313,577.

Specification of Letters Patent. Patented Aug. 19, 1919.

Application filed September 13, 1915. Serial No. 50,332.

To all whom it may concern:

Be it known that I, JOHN H. A. BOUSFIELD, a citizen of the United States of America, residing at St. Johnsbury, in the county of Caledonia and State of Vermont, have invented certain new and useful Improvements in Track-Scales, of which the following is a specification, reference being had therein to the accompanying drawings.

10 The invention relates to track scales and more particularly to the construction of the connection between the extension levers and the so-called fifth lever of the scale. It is the object of the invention to eliminate torsional stresses and to obtain a central connection between the extension levers and fifth lever as hereinafter set forth.

In the drawings:

Figure 1 is a side elevation of the connection;

Fig. 2 is a sectional plan thereof;

Fig. 3 is a transverse section; and

Fig. 4 is a vertical section through the connecting linkage.

25 In the construction of railway track scales, it is usual to provide a double system of extension levers, the end levers of each system being oppositely arranged adjacent to each other and being connected with a so-called 30 fifth lever which transmits the load to the beam. As the supporting pivots for the two extension levers are separated from each other an unsymmetrical loading of the scale will result in unequal stresses upon these 35 pivots and their connections to the fifth lever, which results in a torsional strain upon the latter. This defect I have overcome by my improved construction, which is such that the pull upon the fifth lever is centrally and 40 in the plane of movement thereof; and furthermore, unsymmetrical loading of the scale platform will have no effect in altering the direction of stresses.

45 In detail, A and B are the end extension levers of the two systems which are arranged in alinement with each other. C and D are "nose irons" attached to the ends of the respective levers, the member C being bifurcated to embrace the member D. Each of 50 the furcations of the member C is further bifurcated as indicated at E E' E'' E''. F and F' are knife-edge pivots extending across the furcations E E' E'' E'' respectively. G is a knife-edge pivot secured to

the "nose iron" D and extending between 55 furcations H and H' thereof in alinement with the knife-edge pivots F and F'.

I is the fifth lever which is arranged in a transverse plane and is provided with a knife-edge pivot J. This pivot extends between furcations of the lever I and is arranged beneath the pivots F F' and G, but at right angles thereto. K is a connection between the extension levers and fifth lever, which comprises a bearing for each of the 60 knife-edge pivots and an evener coupling therebetween. Specifically L are the bearings for the pivots F F' and G, which are connected to eye-bar links M by pivot-pins N. The lower ends of these links are 70 connected by pivot-pins O with an evener lever P, and upon the central pivot O is also mounted a hanger Q. This hanger has depending therefrom eye-bolts R and R', which embrace a bearing S for engagement with 75 the knife-edge pivot J. T is a pivot-pin connecting the eye-bolts with the bearing S.

The connecting member constructed as described will transmit the load from either of the systems of levers to the fifth lever 80 without torsional stress upon any of the levers. Thus where the load which is transmitted through the nose piece C differs from that transmitted through the nose piece D, it will nevertheless be central- 85 ized, as the pivots F and F' are arranged symmetrically upon opposite sides of the central plane of the lever. Also the eye-bars M together with the evener lever P will combine the unequal stresses on the levers A 90 and B into a single central stress transmitted through the hanger Q and eye-bolts R to the bearing S and pivot J.

To facilitate the alinement of the pivots the "nose irons" C and D are adjustable 95 upon their respective levers, preferably by connecting them with a screw U extending longitudinally of the levers. Provision is also made for alinement of the eye-bars and to compensate for any slight disalinement 100 of the pivots. This is accomplished by providing the pivot-pins N with threaded portions V on opposite sides of the bearing and clamping nuts W for engaging said threaded portions and the sides of the bearing. 105 Thus by loosening the nuts W the pins may be adjusted longitudinally of their axes or transversely of the bearing blocks. The

eye-bars M preferably engage shoulders on the pins O and are held thereagainst by cotter-pins X. Thus the longitudinal adjustment of the pins O in relation to the bearing blocks will effect a corresponding adjustment of the eye-bars. It is therefore possible by means of these adjustments to eliminate all torsional stresses.

What I claim as my invention is:—

- 10 1. In a track scale, the combination with a plurality of levers and a lever extending transversely thereof, of a connection between said first mentioned levers and said other lever arranged symmetrically of the line formed by the intersection of vertical planes in which the axes of the levers are respectively situated and adjustment means for maintaining said symmetrical arrangement.
- 20 2. In a track scale, the combination with oppositely-extending end levers arranged in a common plane, of a bifurcated nose iron on one end lever and a nose iron on the other end lever embraced thereby, transverse pivots in the furcations of said bifurcated nose iron and said central nose iron in substantial alinement with each other, bearings for engaging the several pivots, a central link for connecting with a fifth lever, and an evener connection between said central link and the several bearings.
- 30 3. In a track scale, the combination with oppositely-extending levers, the end of one being bifurcated to embrace the end of the other, of transverse pivots on said bifurcated and intermediate lever in substantial alinement, independent bearing blocks for engaging the several pivots, links depending from said bearing blocks, an evener lever with which said links are connected, and means for laterally adjusting said bearings with respect to their connecting links to compensate for inaccuracies in alinement of the pivots.
- 40 4. In a track scale, the combination with oppositely-extending levers arranged in the same plane, of a nose iron on one of said levers, a bifurcated nose iron on the opposite lever embracing said first-mentioned nose iron, pivots on the furcations of said bifurcated nose iron and on said first-mentioned nose iron in substantial alinement, and means for adjusting said nose irons with respect to their levers to aline said pivots.
- 50 5. In a track scale, the combination with oppositely-extending levers arranged in a

common plane, of transversely-extending pivots on each of said levers arranged symmetrically with respect to the central plane thereof and in substantial alinement, a fifth lever arranged substantially in the plane of said pivots, a connection between said alined levers and fifth lever including an evener, and means for adjusting said connection to compensate for inaccuracies in alinement. 65

6. In a track scale, the combination with a plurality of extension levers having adjacent ends, one of which has one pivot and the other of which has a plurality of pivots, of a fifth lever having a pivot, a connector 70 between the extension levers and fifth lever comprising a plurality of bearings for engagement with the pivots of the several levers, links pivotally connected to each of the bearings and an evener between said 75 links connected at its center to the link pivotally connected to the bearing of the fifth lever and to the link pivotally connected to the bearing of one of the extension levers and at its opposite ends to the link pivotally 80 connected to the bearings of the other of the extension levers.

7. In a track scale, the combination with oppositely-extending and alined levers, one of said levers having a transverse pivot and 85 the other of said levers having transverse pivots in symmetrical relation to said first mentioned pivot and in substantial alinement therewith, bearings for engaging all of said pivots, an evener lever, means for 90 connecting said evener lever and said bearings, a fifth lever and a link connected centrally to said evener lever and to said fifth lever.

8. In a track scale, the combination with 95 oppositely-extending levers arranged in the same plane, of a nose iron on one of said levers, a bifurcated nose iron on the opposite lever embracing said first-mentioned nose iron, pivots on the furcations of said bifurcated nose iron and on said first-mentioned nose iron in substantial alinement, means 100 for adjusting said nose irons longitudinally of their levers; and means for adjusting said pivots longitudinally of their axes. 105

In testimony whereof I affix my signature in presence of two witnesses.

JOHN H. A. BOUSFIELD.
